UNITED STATES PATENT OFFICE.

THOMAS A. THOMAS, OF AMHERSTDALE, WEST VIRGINIA.

TROLLEY-WIRE CUT-OUT SWITCH.

Application filed July 15, 1921. Serial No. 434,960.

To all whom it may concern:

Be it known that THOMAS A. THOMAS, a citizen of the United States of America, residing at Amherstdale, in the county of Logan and State of West Virginia, has invented new and useful Improvements in Trolley-Wire Cut-Out Switches, of which the following is a specification.

The object of the invention is to provide 10 a simple and efficient cut-out switch for trolley wires used in mines and overhead lines having means for effecting an opening of the circuit without the risk incident to arcing and burning and also adapted as a means 15 of taking up slack to insure a properly taut condition of the trolley wires; and with this object in view the invention consists in a construction and combination of parts of which a preferred embodiment is shown in 20 the accompanying drawings, wherein:—

Figure 1 is a side view of a cut-out switch embodying the invention.

Figure 2 is a longitudinal sectional view of the same.

25 Figure 3 is a plan view.

Figure 4 is a reverse plan view.

Figure 5 is a transverse section on the line 5—5 of Figure 1.

The device consists essentially of a body 30 portion 10 of hard wood or its equivalent having in connection therewith the metallic terminals 11 and 12, preferably of brass or like material of which the extremities 13 and 14 are provided with sockets 15 for the reception of the extremities of the trolley 35 wire elements 16, wedges 17 being employed for securing the wire ends in the sockets.

The terminals have sleeves 11^a and 12^a 40 which receive the ends of the block forming the body portion 10, the sleeve 11^a preferably being secured rigidly to the block by means of bolts 18, and the sleeve 12^a being free to slide upon the block to vary the interval between the terminals to suit the condition 45 of the trolley wire of which the extremities are connected therewith, a screw bolt 19^a being arranged longitudinally of the body portion of the device and serving as a means of effecting the desired relative adjustment of 50 the terminals and of securing the same with the conductor wire at the desired tension.

One of the terminals as for example the member 11 is provided with a fibre extension forming a tongue 19 fitted in a guide 20 55 in the terminal 12 constituting a bridge between the ribs 11^b and 12^b to be traversed by the trolley wheel in its passage from one

trolley wire section to the other, and the movable sleeve 12^a is preferably provided with longitudinally inwardly directed ribs 60 21 operating in grooves 22 in the opposite side surfaces of the block forming the body portion 10.

The means of suspension of the device may consist as illustrated in the drawing 65 of a hanger plate 23 secured to the block and having a slot 24 with which is engaged a bolt 25.

The connection between the terminals is effected by a switch 26 pivoted as at 27 70 on the block for engagement with the contacts 28 and 29 on the terminals and serving to maintain the electrical connection between said terminals. The turning of the switch to break the circuit serves to open the 75 same at both ends simultaneously to avoid making an arc and burning the terminals of the cut-out.

Having described the invention, what is 80 claimed as new and useful is:—

1. A cut-out switch for trolley lines having a body portion consisting of a block of insulating material, terminals carried by said block and provided with means for connection with the adjacent extremities of 85 trolley wire sections, and a switch mounted upon the body portion for simultaneous engagement at its extremities with contacts on said terminals, one of said terminals being longitudinally movable on the block 90 relative to the other terminal and means for securing the same in its adjusted positions.

2. A cut-out switch for trolley lines having a body portion consisting of a block 95 of insulating material, terminals carried by said block and provided with means for connection with the adjacent extremities of trolley wire sections, and a switch mounted upon the body portion for simultaneous 100 engagement at its extremities with contacts on said terminals, said terminals having sleeves fitted upon the block, one of the sleeves being slidably mounted, and a bolt extended through the block for securing the 105 movable sleeve in adjusted positions.

3. A cut-out switch for trolley lines having a body portion consisting of a block of insulating material, terminals carried by said block and provided with means for connection with the adjacent extremities of trolley wire sections, and a switch mounted upon the body portion for simultaneous engagement at its extremities with contacts 110

on said terminals, said terminals being provided at their under sides with trolley guides, one of the terminals being longitudinally movable relative to the block, and 5 a bridge piece connecting the adjacent ends of said guides.

4. A cut-out switch for trolley lines having a body portion of non-conducting material, terminals carried by said body portion and provided with means for connec-

tion with the adjacent extremities of trolley wire sections, means for adjusting said terminals toward each other to tension the connected trolley wire sections, and a switch for electrically connecting and disconnecting 15 said terminals.

In testimony whereof he affixes his signature.

THOMAS A. THOMAS.
